UNITED STATES PATENT OFFICE.

LUCIUS A. CARSON, OF UNIONTOWN, PENNSYLVANIA.

SELF-BINDING HARVESTER.

SPECIFICATION forming part of Letters Patent No. 352,677, dated November 16, 1886.

Application filed July 11, 1885. Serial No. 171,396. (Model.)

To all whom it may concern:

Be it known that I, LUCIUS A. CARSON, of Uniontown, in the county of Fayette and State of Pennsylvania, have invented a new and 5 Improved Self-Binding Harvester, of which the following is a full, clear, and exact description.

My invention relates to self-binding harvesters of that class in which the pressure of 10 the grain on the compressors, as the grain is compacted by the packers on said arms, is utilized, when enough grain has been packed for a bundle, to trip the binding devices into 15 action for binding the bundle, and also to discharge the tied bundle of grain from the machine.

The invention consists in certain novel features of construction and combinations of 20 parts of the harvester, all as hereinafter fully described and claimed.

Reference is to be had to the accompanying 25 drawings, forming part of this specification, in which similar letters of reference indicate corresponding parts in all the figures.

Figure 1 is a rear view of part of a harvester, 30 showing in full lines the tripping mechanism and the mechanism for rotating the compressors to discharge the bound bundle, and also the mechanism for operating the needle-arm and 35 knotter for binding the bundle. Fig. 2 is a reverse view showing in full lines the compressors, the packers, and parts of the tripping and driving mechanism. Fig. 3 is a plan view of the binder, partly in horizontal section; and 40 Figs. 4, 5, 6, 7, 8, and 9 are detail views of parts of the mechanism.

The letters A A' indicate the compressors, 45 against which falls the cut grain passing into the grain chute or receptacle A² from the carrier or elevator of the harvester, (not shown,) said compressors being mounted rigidly on a shaft, a, and are formed with the oppositely-extending end portions, a' a², each of which has a curved edge, a³, into or against which 50 the grain is pressed by the packers B, and an opposite edge portion, a⁴, which, as the shaft a is given a half-turn, discharges the last bound bundle and brings the opposite curved edge, a³, of the compressors into position for receiving the grain for the next bundle, as herein-after more fully explained.

The compressor-shaft a is journaled below

the floor A³ of the grain-chute, which floor is slotted for the passage of the compressors, and also for the passage of the packers B, which latter are connected to opposite cranks on a shaft, b, and to links b', hung loosely on the shaft a, and so as to be operated continuously in the usual manner by means of a belt, b², running to a pulley on the shaft b from a pulley, b³, on a shaft, C, from which the entire binding mechanism receives motion, said shaft C being provided outside of the machine-frame with a chain-wheel, C', which may receive rotary motion by means of a pitman, C², or by 60 a belt connecting it in any approved way with the gearing of the harvester.

The central or main compressors, A A', are arranged for operation at opposite sides of the needle-arm D, and as closely as may be thereto, 70 and the outside compressors, A' A', are intended to support the butts and heads of the grain as it is received, packed, bound, and discharged.

The needle-arm D is hung loosely on the 75 compressor-shaft a, and near the shaft is provided with a toothed segment or rack, d, which engages a segmental rack, d', which is rigid on a shaft, D', which is journaled in the machine-frame below the packer-shaft b and carries rigidly outside the frame the crank-arm D², to which is pivoted one end of a rod, D³, the other end of which is pivoted to a shorter crank-arm, E', on the end of a shaft, E, which extends through the rigid arm F, fixed to the 85 frame, and at the other end of which arm F, and directly above the compressors and needle, are arranged at G the knotter devices which are operated from or by the shaft E.

The knotter devices will not be herein shown 90 or described, as they form no part of the present invention, and will be the subject-matter of another application for Letters Patent shortly to be made by me, it sufficing here to state that the knotting devices G tie the knot at or 95 immediately after the point of the needle D is raised to them with the end of the cord.

The relative lengths of the crank-arms D² E' are such that as the chain-wheel H, which receives continuous motion from the chain-wheel C' by means of chain-belt H', causes the shaft E to make a complete revolution by means of clutch devices presently explained, the shaft D' will merely be rocked to cause the needle-

arm D to rise to and be lowered from the knotter at G by the engagement of the racks d d' with each other.

The needle-arm D has the usual eye, d', for the passage of the cord, and the usual guard, d', to separate the bundle of grain being bound from the grain descending the chute A' above the needle-arm as the tying progresses.

The mechanism for automatically tripping the binding devices into action is arranged as follows: The chain-wheel H is loose on shaft E, and has an internal gear, h, formed on the inner face of its periphery, and in the body of the wheel I, which is fast on the shaft E and is placed next the wheel H, is journaled a short shaft, i', which carries fixedly at one end the pinion i, which meshes with the internal gear, h, of wheel H, and carries fixedly at its other end the clutch-wheel I', which preferably has diametrically opposite ratchet-teeth i' i'', which are adapted to be engaged by the tooth j of a dog, J, which is pivoted at j' to the inner face of the wheel I, and is forced by a spring, j'', held to this wheel, into contact with the clutch-wheel, as in Fig. 6, when the trip-lever K is not holding the dog J back or away from said wheel I', and against a stop-pin, j', in the wheel, said trip-lever K being operated to hold the dog J back, as aforesaid, by means of a trip-arm, L, which is fixed to the compressor-shaft a, and has opposite ends, l l', which alternately act on the trip-lever, as hereinafter more fully explained.

The trip-lever K is pivoted at k to the harvester-frame, and consists of two parts, a main part, K', which has an end portion, k', which strikes the edge j' of the dog J to lift its tooth j from the clutch-wheel I', and an elastic or spring part, K'', which is held by a screw or otherwise to the part K', and has a stud, k'', on its outer end, which stud is adapted to enter a notch, i'', in the wheel I when the trip-lever K is moved by the trip-arm L against the wheel I, and the part K'' of lever K also has a stud, k'', which, as the stud k'' enters the notch i'' of wheel I, acts against the inclined toe j'' of the dog J, to hold said dog out of engagement with the clutch-wheel I' after it has been disengaged therefrom by the end part k' of lever K. (See Figs. 1 and 2.)

The trip-lever K is made in the two parts K' K'', to allow its part K'' to yield as the end k'' of part K'' is forced inward by arm L to disengage the dog J from clutch-wheel I' as the stud k'' rides on the periphery of wheel I prior to the springing of said stud into the notch i'', as will be understood from Fig. 6. A spring, k'', held to the harvester-frame, acts on the trip-lever K, after the trip-arm L has been moved from the lever, to swing the studs k' k'' of the lever away from the dog J and clutch-wheel I', to allow the dog to engage the clutch-wheel to cause the wheel I and its shaft E to be rotated by and with the wheel H to operate the binding and discharging mechanism, as hereinafter described, and a stop-pin, k'', limits the throw of the lever K by the spring

k'', and holds the lever in proper position to again be operated on by the trip-arm L.

It will be understood that when the binding and discharging mechanisms are not in operation, and the dog J is disengaged from the clutch-wheel I', the latter will be continuously rotated by the free-running wheel H and gears h i, and when the dog J is allowed to engage the clutch-wheel I' the wheels H I I' and dog J rotate together, and the shaft i' and its pinion i and clutch-wheel I' then will not rotate independently.

A single shoulder, i'', may be provided on the clutch-wheel I', or more than two shoulders; but the two shown are at present preferred, as they insure almost instant engagement of the dog J with the clutch-wheel when the dog is released from the trip-lever K, the pinion i', which drives the clutch-wheel, making about five turns to one turn of the chain-wheel H, by whose gear h it is driven.

The trip-arm L is fixed to the compressor-shaft a, preferably by being passed through said shaft, (see Fig. 8,) and on the shaft is placed loosely by its hub m the pinion M, said hub being notched at m' around the trip-arm L, which arm thus is caused to turn the shaft a when the pinion M is turned; and these hub-notches m are wider or longer than the thickness of the trip-arm, so that said arm may be rotated sufficiently with the shaft a and independently of a rotation of pinion M, and against the tension of a spring, N, to allow the end of the trip-arm L to be moved from the trip-lever K, as in Fig. 7, by the pressure of the grain on the compressors A A', when sufficient grain shall have been compressed by the packers B to form a bundle or gavel of proper size in the chute, and at the same time permit engagement of the clutch mechanism to start the binding devices, as hereinafter more fully explained.

The spring N is coiled around the shaft a, and enters by its one end, n, a slot made across the shaft, and bears by its other end, n', on a pin, m', fixed in the pinion M. The tension of spring N thus controls the pressure at which the compressor-shaft a shall be turned by the compacting of the grain against the compressors, and so as to trip the arm L from lever K at the proper time for starting the binding mechanism. The tension of the spring N may be regulated as required by setting its end w' against any one of a series of pins, m', fixed to pinion M, or in any other approved way.

To the harvester-frame, or a gudgeon fixed therein, is journaled a pinion, O, which meshes with the pinion M, and has a circumferential flange, P, which is provided with diametrically-opposite notches p p', into which notches alternately a stud, r, on a dog, R, pivoted at r' to the harvester-frame, is adapted to be forced by a spring, S, for locking the pinions O M at rest, and thereby holding the compressors A A' at rest against the pressure of the packers B, as the grain to form a full-sized bundle is packed against the arms, and until

a stud or pin, T, on the inner face of wheel I, strikes the extremity r^2 of the dog R to lift its stud r from a notch, p, just prior to the engagement of the segment of teeth U on the 5 wheel I with the teeth of the pinion O, to give said pinion a half-turn, the stud r meanwhile resting on the periphery of the flange P until the wheel O stops after the teeth U have passed, and with the opposite notch, p, directly under the stud r of dog R, which stud then is forced into the notch by the spring S, to lock the mechanism as before.

The continuous operation of the mechanism is as follows: We will suppose the parts to be in 15 the positions represented in Figs. 1 and 2, with the end l of trip-arm L holding the stud k^2 of trip-lever K into the notch i^2 of wheel I, to lock said wheel, and the knotted devices at rest, and also with the stud k^3 of lever K holding 20 the tooth j of dog J away from the clutch-wheel I', and with the pinions O M and the compressors A A' also held at rest by the dog R, the chain - wheel H meanwhile being revolved by the belt H' in the direction of arrow 25 1, and the grain being meanwhile packed in a gavel against the arms A A' by the packers B. When sufficient grain has been packed in the grain-chute to form a bundle, the excessive pressure of the grain on the arms A A' 30 35 will turn said arms and their shaft a forward and against the tension of the spring N, so as to trip the end l of arm L from the end of lever K, and the spring k^3 then presses the lever to withdraw its stud k^2 from the notch i^2 of wheel I to allow the wheel to revolve, and simultaneously the studs k^3 k' will be withdrawn from dog J to allow the spring j^2 to force its tooth j against one of the shoulders i^2 of clutch-wheel I', as in Fig. 7, and so as to start 40 45 the binding devices by rotating the wheel I and its shaft E. The effect will be to rotate the shaft E and crank-arm E' and rock the crank-arm D' and its shaft D', so as to raise the needle-arm D, by the segmental racks d d', to the 50 55 knotter devices at G, which tie the gavel or bundle and cut the cord or band; and just as the needle arm D is started back from the knotter by the reverse movement of the shaft D' the stud T on the wheel I strikes the end r^2 of dog R to raise its stud r from the notch p of the flange P on pinion O, and the segment of teeth U on wheel I instantly engages the teeth of pinion O, to turn said pinion in the direction of arrow 2 for a half-revolution, or until 60 65 70 the stud r of dog R engages the notch p opposite the one it had first rested in. This half-turn of the pinion O had turned the pinion M and trip-arm L and shaft a in the direction of arrow 3 for a half-revolution, and thereby had carried the compressors A A' around a like distance, so that the tied bundle or gavel of grain was discharged by the edges a' of the arms, which previously had stood below the floor of the grain-chute, and the opposite 75 80 85 curved edges, a', of the arms now rest and are locked in position to receive the next gavel of grain, the back movement of the needle-arm

D being timed so that the arm will not let the grain fall down the chute until the compressors are in proper position to receive the grain. 70 As the half-turn of the compressors was being completed the end l' of the trip-arm L had acted on the trip-lever K, to again throw its stud k' into the path of the dog J to lift the dog from the clutch-wheel I', and immediately 75 afterward the stud k^2 had sprung into the notch i^2 of wheel I to stop this wheel, as its segmental teeth U had escaped the teeth of pinion O, and the stud k^3 had engaged the lifter-dog J, and the parts then rest in their first positions until the excessive pressure of the grain on the compressors A A' will trip the end l' of the arm L from the lever K to start the binding devices again into operation, as above described. 80 85

But one gavel-compressor may be fixed to the shaft, against which arm the grain may be pressed by the packers B, as will readily be understood.

Having thus fully described my invention, I 90 claim as new and desire to secure by Letters Patent—

1. In self binding harvesters, the combination, with the grain-chute and compressors held to a shaft a, and adapted to receive the 95 grain, of a trip-arm, L, fast on shaft a, a spring-pressed trip-lever, K, having a stud, k^2 , a wheel, I, fast on the knoter-shaft E, and provided with a notch, i^2 , to which stud k^2 is adapted, a drive-wheel, H, loose on shaft E, and provided 100 with an internal gear, h, a shaft, i', journaled in wheel I, and carrying a pinion, i, meshing with gear h, and a clutch-wheel, I', a spring-pressed dog, J, pivoted to wheel I, and adapted to engage the clutch wheel, a stud, k^3 , on trip-lever K, adapted to hold dog J out of engagement with the clutch-wheel, teeth U on wheel I, a pinion, O, adapted to be engaged by teeth U, a peripherally-notched flange, P, on pinion O, a dog, R, adapted to the notches of flange 105 P, a stud, T, on wheel I, a pinion, M, loose on shaft a, and having a hub, m, slotted at m', loosely around the trip-arm L, and a spring, N, connected to shaft a and pinion M to allow independent forward movement of the shaft a, 110 and its trip-arm L, for tripping the binding mechanism into action, substantially as herein set forth.

2. In self-binding harvesters, the combination, with the grain chute and compressors fixed to a shaft, a, to extend opposite ways from said shaft alternately to receive and discharge the gavels of grain, substantially as specified, of a trip-arm, L, fast on shaft a, and having opposite acting ends l l', a spring-pressed trip-lever, K, having a stud, k^2 , a wheel, I, fast on the knoter-shaft E, and provided with a notch, i^2 , to which stud k^2 is adapted, a drive-wheel, H, loose on shaft E, and provided with an internal gear, h; a shaft, i', journaled in wheel 120 I, and carrying a pinion, i, meshing with gear h, and a clutch-wheel, I', a spring-pressed dog, J, pivoted to wheel I and adapted to engage the clutch - wheel, a stud, k^3 , on trip-lever K,

adapted to hold dog J out of engagement with the clutch-wheel, teeth U on wheel I, a pinion, O, adapted to be engaged by teeth U, a flange, P, on pinion O, and notched at p p, a dog, R, having a stud, r, adapted to notches p p, a stud, T, on wheel I, a pinion, M, on shaft a, and having a hub, m, slotted at m' loosely around the trip-arm L, and a spring, N, connected to the shaft a and pinion M to allow independent 10 forward movement of the shaft a, and its trip-arm L, for tripping the binding mechanism into action after each half-revolution of the compressors, substantially as herein set forth.

3. In self-binding harvesters, the combination, with the grain chute, the compressors, their shaft a, and trip-arm L on shaft a, of a drive-wheel, H, loose on the knotted-shaft E, and provided with a gear, h, the wheel I, fast on shaft E, and notched at i³, a shaft, i', journal in wheel I, and carrying a pinion, i, and clutch-wheel, I', a spring-pressed dog, J, on wheel I, and adapted to engage the clutch-wheel, and a trip-lever, K, provided with studs acting to lift the dog J from clutch-wheel I' and hold the dog from said wheel, and a stud entering notch i³ of wheel I to lock it at rest, substantially as herein set forth.

4. In self-binding harvesters, the combination, with the compressors, their shaft a, the trip-arm L, the wheel I, notched at i³, a clutch dog, J, pivoted on wheel I, and provided with an edge, j⁴, and angular face j⁵, substantially as specified, of a spring-pressed trip-lever, K, made in two parts, K', K², the rigid part K' 35 provided with the end stud, k', and the elastic part K² provided with a stud, k², for stopping the wheel, and a dog holding stud, k³, substantially as herein set forth.

5. In self-binding harvesters, the combination, with the grain-chute, the compressor shaft a, and knotted-shaft E, of a wheel, I, fast on shaft E, means for operating said wheel I, the pinion M on the shaft a, and adapted to revolve said shaft, the pinion O, meshing with pinion M, and provided with a flange, P, notched at p, a dog, R, adapted to the notches p, and a trip-stud, T, and teeth U on wheel I, substantially as herein set forth.

6. In self-binding harvesters, the combination, with the grain-chute, the compressors, their shaft a, the trip-arm L, fixed to shaft a, and the trip-lever K, of a pinion, M, placed loosely by its hub m on shaft a, and said hub having slots m', allowing independent forward 55 movement of the shaft a, and arm L for tripping the lever K to start the binding devices, substantially as herein set forth.

7. In self-binding harvesters, the combination, with the compressors, their shaft a, the trip-arm L, and trip-lever K, of the spring N, held to shaft a, and to its driving-pinion M, so its tension controls the movement of the compressors and trip-arm L as the binding mechanism is tripped into action, substantially as herein set forth. 60 65

8. The combination, with the shaft E, the wheel H, having internal gear, h, and loosely mounted on shaft E, and wheel I, fast on shaft E, of the shaft i', pinion i, clutch-wheel I', and spring-dog J, substantially as set forth. 70

9. In a self-binding harvester, the combination, with the shaft E, having crank-arm E', wheels H and I, and mechanism for locking said wheels together, shaft a, carrying gavel-arms A, mechanism for revolving and holding 75 said shaft a, and the needle D, loosely mounted on shaft a, and provided with the gear-segment d, of the shaft D', having crank-arm D', the gear-segment d, and the connecting-rod D', substantially as set forth. 80

10. In a self-binding harvester, the combination, with the shaft E and wheel I, having gear-segment U and a pin, T, of the shaft a, carrying gavel-arms A, the gear M on shaft a, the pinion O, provided with disk P, having 85 notches p, and the spring-pawl R, having studs r and r', substantially as set forth.

11. In a self-binding harvester, the combination, with the wheel H, having internal gear, h, the wheel I, the shaft i', carrying clutch-wheel I', and pinion i, and the spring-dog J, having tooth j and stud j⁵, of the shaft a, carrying the gavel-arms A, the arm L on shaft a, the pinion M, mounted loosely on said shaft and having a slotted hub engaging the arm L, 95 the spring N, and the spring-lever K, engaging the dog J and arm L, substantially as set forth. 90

12. In a self-binding harvester, the combination, with the shaft E, carrying wheel I, provided with gear-segment U and pin T, wheel H, loosely mounted on shaft E, mechanism for locking said wheels H and I together, shaft a, carrying gavel-arms A, pinion M, spring N, and arm L, of the gear O, having disk P, provided with notches p, spring-pawl R, and 100 lever K, having arm k', and spring-arm K', substantially as set forth. 105
